UNITED STATES PATENT OFFICE.

FLOY E. DAVENPORT, OF CALLAWAY, NEBRASKA.

ANIMAL GUN-TRAP.

1,347,255.

Specification of Letters Patent.

Patented July 20, 1920.

Application filed October 12, 1917. Serial No. 196,142.

To all whom it may concern:

Be it known that I, FLOY E. DAVENPORT, a citizen of the United States, residing at Callaway, in the county of Custer, State of Nebraska, have invented a new and useful 5 Animal Gun-Trap; and I do hereby declare the following to be a full, clear, and exact description of the invention, such as will enable others skilled in the art to which 10 it appertains to make and use the same.

The invention relates to gopher guns and the like and has for its object to provide a gun of this character comprising a pivotal gun barrel pivotally movable in a vertical 15 plane and pivoted at a point intermediate its ends, said barrel being provided with a breech adapted to move into registration with a block provided with a firing pin, also to provide spring detent means for 20 holding said gun in firing position; said detent means comprising a spring arm having a lug which lug coöperates with the periphery of the breech end of the gun and an aperture in said breech.

25 A further object is to so position the spring arm carried lug and the aperture in the gun barrel so that the gun barrel will be held in a horizontal position.

In practical fields the details of construction may necessitate alterations falling 30 within the scope of what is claimed.

The invention comprises further features and combination of parts as hereinafter set forth shown in the drawings and claimed.

35 In the drawings:—

Figure 1 is a view in plan of the improved animal gun trap constructed in accordance with the invention.

Fig. 2 is a view in side elevation.

40 Fig. 3 is a rear view.

Fig. 4 is a sectional view on line 4—4 of Fig. 1.

Fig. 5 is a sectional view on line 5—5 of Fig. 1.

45 Referring more especially to the drawings 1 designates a base, upwardly from which, a breech block 2 extends. Forwardly of the breech block, a U-shaped bracket 3 is secured by screws 4 to the base 1. Between 50 the arms of said U-shaped bracket and on the pin 5 a transverse lug 6 of a gun barrel 7 is rockably mounted. The gun barrel, therefore may be tilted, so that its forward end will lower and its cartridge receiving end will raise. A conventional form of firing pin 8 is mounted in the breech block,

whereby its rear end may protrude beyond the rear face of the block normally. The U-shaped bracket is arranged with relation to the breech block, whereby the gun barrel 60 will axially align with the firing pin, when the rear or butt end of the barrel is lowered to the position shown in Fig. 4. By this arrangement and construction, the firing pin will align with the cap of the cartridge. A 65 spring arm 9 has its lower angle end 10 secured at 11 to the base 1, so that its upper end portion (which is provided with an inwardly extending lug 12) may engage the side of the gun barrel, whereby the lug 12 70 may enter a depression 13 of the barrel, to hold the barrel axially in alignment with the firing pin, when firing a cartridge. To remove the shell the thumb of the operator engages the curved end portion 14 of the arm 9, springing the arm outwardly, so as to disengage the lug from the depression. The forward end of the barrel is then tilted 75 downwardly, the cartridge receiving end consequently rises, whereby the shell may be extracted. A bell crank detent 15 is pivotally mounted on a post 16. One arm of this bell crank detent has a laterally extending lug forming a shoulder 17, and to the extremity of the other arm of said detent, one end of a rod 18 (which is mounted in a guide eye 19 of an upstanding rod 20) is 80 pivotally connected. The forward end of the rod 18 has a head member 21. Pivoted upon a post 22 by means of a screw 23 is a lever 24, which is so arranged that its end portion 25 may engage the shoulder 17. By means of the bell crank detent, the lever 24 is held away from and out of contact with the firing pin, against the action or tension 85 of the spring 26, one end of which is connected at 27 to the lever 24, and its other end to a post 28, which rises upwardly from the base 1. A signal member is pivoted by means of a screw 29 on a post 30, and its tail end 31 engages a lug 32 of the lever 24. A spring 33 has one end connected at 34 to the pivoted leg of the signal, and its other end to a pin 35 which rises upwardly from the base, the spring serving to hold the tail end 31 of the leg against the lug 32 of the lever 24, and the signal end 36 of the signal in position to indicate that the animal gun trap is loaded and set. In arranging the gun trap for use, the barrel is first tilted, so that 95 the cartridge may be inserted. The barrel is then arranged, whereby its center will axi-

ally aline with the firing pin. The lever 24 is then set so as to be held out of contact with the firing pin by the bell crank detent, and the signal arranged. The trap is then ready 5 for use for killing burrowing animals, such as gophers and moles. The mound of earth at a proper location of the path of the animal (gopher) is excavated sufficiently, to permit the animal gun trap to be introduced 10 in the excavation, the trap set, and the barrel of the gun arranged in alinement with the burrow, and also the head member 21 partially in the path of the animal which may pass along the burrow. When the animal 15 comes in contact with the head member 21, the rod 18 is actuated so as to tilt the bell crank detent on its pivot, releasing the lever 24, which, under the action of the spring 26 is swung forwardly to contact with the 20 firing pin. The cartridge is then fired, and being that the barrel is in alinement with the burrow, the projectile will consequently strike and kill the animal. When the lever 24 is actuated by the spring 26, the signal is 25 released, and by means of the spring 33, the leg of the signal is thrown in contact with the abutment lug 37, in which case the signal is then disposed to indicate that the trap has been sprung.

The invention having been set forth what 30 is claimed as new and useful is:—

In an animal trap, a base provided with an upstanding breech block, a firing pin in said breech block, a pair of spaced trunnions mounted on the base, a gun barrel tiltably 35 pivoted between said trunnions, and having its axis in horizontal alinement with the firing pin, a recess in one side of the gun barrel in the rear of the trunnions, a spring arm rising upwardly from the base, said spring 40 arm being provided with a right angled lug adapted to be received by the recess in the gun barrel when the gun barrel is in horizontal position, said spring arm and lug being so positioned that when it is being 45 moved to its firing position after loading operation the lug carried by the spring arm will be engaged by the convexed surface of the gun barrel and cam over said surface until it springs into the recess. 50

In testimony whereof I have signed my name to this specification in the presence of two subscribing witnesses.

FLOY E. DAVENPORT.
